REVERSIBLE LATCH MECHANISM

Albert F. Lickteig, Jr., Grand Rapids, Mich., assignor, by mesne assignments, to Harloc Products Corporation, a corporation of Connecticut

Application September 9, 1948, Serial No. 48,456

4 Claims. (Cl. 393—244)

1

This disclosure is a continuation in part of that described in the application of Albert F. Lickteig, Jr., Serial No. 30,755, filed on June 3, 1948, and entitled "Latch Mechanism." The application referred to describes a latch which is adapted to have its direction of locking action changed by an adjustment which is made without requiring the removal of the mechanism from its position in the door. This change of the direction of locking action is accomplished by removing the front plate, and reinstalling the same after rotating it 180° in a plane parallel to its normal position. Such re-positioning of the front plate serves to select which of two locking surfaces of the bolt are to be presented in locking position. The supporting structure for the bolt which maintains it against forces encountered in locking are such that they cooperate with the bolt in either of two positions. The supporting structure is also of such a nature that the bolt becomes disengaged therefrom in the very early stages of the retracting movement. Such disengagement permits the bolt to be rotated slightly by the action of the striker plate as the door is pulled open, and the locking surface thereby assumes enough of a slant to urge the bolt inwardly against the action of suitable springs. In this manner a door may be pulled open after actuating the knob a small fraction of the total travel thereof normally associated with opening a door.

As described in the above identified application, a latch device having these characteristics makes possible the installation of such devices within the door as the door is being manufactured. This type of installation obviously effects considerable economy over the usual practice in which the carpenter installs all the hardware as the door is hung in position. This arrangement also makes possible the removal of a door from a position in which it has been hung, and the installation thereof in a new location in which the direction of swing from closed to open is different from that of the first installation. The accommodation of the latch to the new direction of locking action is effected by the adjustment to the front plate above described.

The present disclosure also provides a support means for a bolt which becomes partially disengaged as the bolt is slightly withdrawn from locking position. While the supporting means for the bolt in the above identified application provides a clamping action between opposed surfaces on the bolt, the support means contemplated by the present invention comprises a

guideway formed in the case of the latch mechanism, the guideway being engaged by a pin which is rigidly associated with the bolt. The cooperation of the pin with the guideway replaces one of the supporting surfaces of the mechanism described in the above identified application. The present invention has several advantages over that described in the application referred to, both as to the manner of supporting the bolt in locking position, and also as to the support given the bolt while in the retracted position. In the preferred form of this invention, the guideway is parallel to the retracting movement of the bolt, and is formed on a plane of symmetry of the case. In a modified form of this invention, the guideway has two or more branches, each carrying the pin to a point where the bolt is positioned to present a particular locking surface for locking action. The cooperation of the pin with the guideway definitely maintains the bolt at one point along a fixed line of movement. The bolt, in effect, rotates about this point as either of the two locking surfaces are positioned for locking action. In the preferred form, the engagement of the bolt with the front plate as the bolt moves outwardly under the urging of the various springs of the mechanism causes the bolt to be positioned according to the location of the aperture in the front plate with respect to the guideway above described. The guideway of the modified form of this invention can be so proportioned as to have either the same action, or require the full retraction of the bolt and manual adjustment to determine the bolt position. In locking position, a suitable bearing surface on the bolt similar to that described in the above identified application cooperates with the front plate in the same manner as indicated therein. The combination of such fixed support with the bolt support provided by the pin and guideway completes the angular positioning of the bolt against the forces encountered in locking. It is of course possible to use both types of guideways and thereby replace the bearing surfaces on the bolt entirely.

The various features of this invention will be described in detail by an analysis of the particular mechanisms which are illustrated in the accompanying drawings. In these drawings,

Figure 1 is a section through the case taken on a horizontal plane, and showing the various components of the preferred form of this invention in operating position.

Figure 2 is a vertical section through the

2

same mechanism indicated in Figure 1, the two views being drawn in projection.

Figure 3 is a section taken on the plane 3-3 of Figure 1.

Figure 4 is a section taken on a horizontal plane of a modified form of this invention.

Figure 5 is a vertical section through the mechanism indicated in Figure 4.

Referring to Figure 1, the latch mechanism generally indicated at 10 is shown provided with a retracting mechanism designated as 11. When the mechanism 10 has been installed in a door, suitable transverse actuating bars are installed to cooperate with retracting mechanism 11, the operation of which is to induce a reciprocating motion to the crosshead 12, and to induce the retraction of the bolt 13 by means of the retracting link 14. The movement of the crosshead 12 is transmitted to the retracting link 14 by means of the engagement of the enlarged end 15 of the link with a portion of the forward end of the crosshead 12. Since the details of the retracting mechanism form no part of the present invention, this section of the device will not be described at length. A retracting mechanism in all respects similar to that indicated in these drawings will be found described in the application referred to previously.

The bolt 13 is provided with the bearing surfaces 16 and 17 which cooperate with the fixed support provided by the bolt-receiving aperture of the front plate 18. With the bolt in the position indicated in Figure 1, the surface 19 may be considered to be in "locking" position, and the surface 20 will be referred to as in "slant" position.

The bolt 13 is provided with the transverse pin 21 which projects from either side of the bolt to engage suitable guideways 22 and 23 which are preferably formed integrally with the case 24, but may be associated with any fixed structure of the latch mechanism. The pin 21 also provides the pivot connection between the bolt and the retracting link 14. The supporting structure comprising the edge of the front plate aperture and the guideways 22 and 23 cooperate to completely support the bolt 13 against forces generated by the locking action. The lateral locking force is resisted by the bearing surface 16 and its related support, while the counteracting moment which is created by such locking force is resisted by components of force contributed by the guideway and the bearing surface 16.

As the bolt 13 moves inwardly under the action of the retracting mechanism, the bearing surface 16 becomes disengaged from the surface of the front plate aperture with which it is shown cooperating in Figure 1. As soon as such disengagement is completed, the bolt becomes free to rotate to a limited extent in a clockwise direction about the axis of the pin 21. Such rotation will be limited by the engagement of surface 20 with a portion of the front plate aperture. As a door is slammed shut, the striker plate on the door jamb will engage the slant surface 20, creating a component of force which urges the bolt inwardly. The bolt 13 is secured against further angular rotation in a counterclockwise direction from that indicated in Figure 1 by either the action of the surface 19 bearing against the front plate aperture, or by the engagement of the shoulder

25 with the upper portion of the case 24, as seen in Figure 1. A shoulder 26 performs this same function when the locking direction of the bolt is changed so that the surface 20 is disposed perpendicular to the front plate.

The bolt 13 is continuously biased outwardly (until the retracting mechanism is actuated) by the action of spring 21 which surrounds the retracting link 14. The spring 21 operates between the forward face of the crosshead 12 and suitable retaining shoulders upon the forward end of the retracting link 14. The spring, in effect, forces the retracting link to urge the bolt into locking position. Stop means are provided 10 to limit such outward movement of the bolt so that the bolt at no time proceeds beyond the locking position indicated in Figures 1 and 2. Such limiting action is preferably accomplished by permitting the pin 21 to engage a fixed structure such as the back plate 28, or by simply relying on the action of the enlarged portion 15 of the link 14 as it contacts the transverse portion of the crosshead 12. The link 14 is 15 slidably retained in a suitable aperture in the forward portion of the crosshead 12, such aperture being large enough to admit the smaller dimension of the link 14, but not being large enough to permit passage of the enlarged end 15. As the door is slammed shut, the bolt 13 moves inwardly with such movement resisted by spring 21, and with the link 14 sliding through the aperture in the crosshead. As the retracting mechanism is manually actuated, such actuation is resisted by the action of the spring 20 29.

If it is desired to change the direction of locking action of the bolt 13, it is merely necessary to remove the front plate 18 from the position indicated and to rotate the same in an amount 40 equal to 180° and re-install it within the confines of the locating shoulders 30. This adjustment to the front plate serves to re-position the bolt-receiving aperture with respect to the guideways 22 and 23 and to maintain the bolt in a locking position in which the surface 20 is perpendicular to the front plate rather than surface 19 as is now shown. As the bolt moves outwardly from retracted position, the engagement 45 of the converging portion of the bolt with the aperture tends to cause the bolt to move naturally into whichever of the locking positions has been determined by the installation of the front plate. The front plate is secured in position by the action of wood screws which are inserted at 31 and which secure the latch mechanism 10 within the door.

Referring to Figures 4 and 5 of the drawings, a modified form of this invention is illustrated involving a different type of guideway from that 60 illustrated in Figures 1, 2, and 3. In this form of the invention, the bolt 32 is provided with the laterally extending pins 33 and 34 which are preferably co-axial, and cooperate with the guideway 35 which may be formed as indicated in the sides 65 of case 36. The guideway 35 comprises the upper portion 37, the lower portion 38, and the vertical connecting portion 39. Since the guideway 36 has its exact opposite upon the side of the case not shown in Figure 4, the reference characters may be considered to indicate the guideway system generally. It is clearly apparent that as the door carrying the latch mechanism in Figure 4 is slammed shut, the bolt moves 70 inwardly with the pin 33 following the upper

portion 31 of the guideway 35. As the bolt 32 moves inwardly, the pin 33 finally reaches a position opposite the vertical section 39 of the guideway 35, and it is then possible to use a screw-driver or other implement which is applied to the surface 40 of the bolt, and tip the bolt into a position in which the surface 41 stands perpendicular to the front plate 18. The length of the horizontal sections 37 and 38 of the guideway 35 determines the point to which the bolt must move before such adjustment can be made. It is possible to proportion these guideways so that the pins 33 and 34 become disengaged in the early stages of retraction of the bolt. With the latter arrangement, it is possible to permit the aperture of the front plate 18 to determine the locking position of the bolt, provided that the length of the horizontal portions 37 or 38 is such that the pins 33 and 34 are not engaged until the front plate has caused the bolt 32 to tip into correct locking position for engagement with the front plate aperture.

The outward movement of the bolt 32 beyond locking position can be prevented in any one of a number of ways. For illustrative purposes, the stop shoulders 42 and 43 are shown which cooperate with the rear portion of the back plate or any similar fixed structure. It is also practical to limit the outward movement of the bolt through the engagement of the pins 33 and 34 with the forward portion of the guideway 35. The balance of the retracting mechanism including the retracting link and the various biasing means illustrated in Figures 4 and 5 are the same as those shown in Figures 1, 2 and 3.

When it is desired to change the direction of locking action of the modified form of this invention, it will of course be necessary to reverse the position of the front plate in the same manner as described in connection with the preferred form of the invention. With the guideway proportioned as shown in Figure 4, the change in direction of locking action of the bolt is accomplished by removing the front plate 18 and rotating it 180° in a plane parallel to its normal position. Before re-installation of the plate, the retracting mechanism is actuated to a point where the pin 33 appears opposite the vertical section 39 of the guideway 35. At that point the bolt may be either manually forced to a position in which the pin 33 is disposed to engage the lower guideway 38, or a screw-driver or other instrument may be inserted under the surface 40 to accomplish this purpose.

The particular mechanisms which are shown in the accompanying drawings and which are discussed herein are presented for illustrative purposes only, and are not to be considered as limitations upon the scope of this invention established by the appended claims.

I claim:

1. In a latch mechanism having retracting means, the combination of: a bolt having a plurality of converging locking surfaces, any one of which may be positioned to engage a keeper, and bearing surfaces associated respectively with each of said locking surfaces; coaxial projections on opposite sides of said bolt, said sides being substantially perpendicular to said locking surfaces; first support means including fixed guideways disposed to cooperate with said projections to rotatably support and to guide said bolt to and from a retracted position; second support means including a supporting surface disposed to be engaged by one of said bearing surfaces upon pro-

jection of said bolt toward latching position to maintain the locking surface associated with said bearing surface in keeper-engaging position, said one bearing surface being disengaged from said supporting surface at an inward position of said bolt from extreme projection; biasing means urging said bolt outwardly; and stop means preventing outward movement of said bolt beyond locking position.

10 2. In a latch mechanism having retracting means, the combination of: a bolt having a plurality of converging locking surfaces, any one of which may be positioned to engage a keeper, and bearing surfaces associated respectively with each of said locking surfaces; coaxial projections on opposite sides of said bolt, said sides being substantially perpendicular to said locking surfaces; first support means including fixed guideways disposed to cooperate with said projections to rotatably support and to guide said bolt to and from a retracted position; second support means including a front plate having a bolt-receiving aperture providing a supporting surface disposed to be engaged by one of said bearing surfaces upon projection of said bolt toward latching position to maintain the locking surface associated with said bearing surface in keeper-engaging position, said one bearing surface being disengaged from said supporting surface at an inward position of said bolt from extreme projection; biasing means urging said bolt outwardly; and stop means preventing outward movement of said bolt beyond locking position.

35 3. In a latch mechanism having retracting means, the combination of: a bolt having a plurality of converging locking surfaces, any one of which may be positioned to engage a keeper, and bearing surfaces associated respectively with each of said locking surfaces; coaxial projections on opposite sides of said bolt, said sides being substantially perpendicular to said locking surfaces; first support means including fixed guideways disposed to cooperate with said projections to rotatably support and to guide said bolt to and from a retracted position; second support means including a front plate having a bolt-receiving aperture providing a supporting surface disposed to be engaged by one of said bearing surfaces upon projection of said bolt toward latching position to maintain the locking surface associated with said bearing surface in keeper-engaging position, said one bearing surface being disengaged from said supporting surface at an inward position of said bolt from extreme projection; mounting means for said front plate, said mounting means being eccentric to said aperture; biasing means urging said bolt outwardly; and stop means preventing outward movement of said bolt beyond locking position.

60 4. In a latch mechanism having retracting means, the combination of: a bolt having a plurality of converging locking surfaces, any one of which may be positioned to engage a keeper, and bearing surfaces associated respectively with each of said locking surfaces; coaxial projections on opposite sides of said bolt, said sides being substantially perpendicular to said locking surfaces; first support means including fixed guideways having a plurality of projection-engaging portions, each of said portions being disposed to cooperate with said projections to rotatably support and to guide said bolt to and from a retracted position; second support means including a supporting surface disposed to be engaged by one of said bearing surfaces upon projection of said bolt

toward latching position to maintain the locking surface associated with said bearing surface in keeper-engaging position, said one bearing surface being disengaged from said supporting surface at an inward position of said bolt from extreme projection; biasing means urging said bolt outwardly; and stop means preventing outward movement of said bolt beyond locking position.
